AIR HEATER FOR FURNACES

Giuseppe Alfisi, Brooklyn, N. Y.

Application November 29, 1938. Serial No. 242,881

1 Claim. (CL 110—75)

This invention relates to air heaters for furnaces, and has for an object to provide an improved construction which is simple and yet effective in its operation to cause the combustion of gases as well as cause an appreciable saving in coal while producing the same amount of heat.

Another object of the invention is to provide a heater air supply device adapted to be connected to the door of an ordinary heating furnace so as to swing inwardly and outwardly therewith.

A further object of the invention is to provide an air heater for supplying heated air to the gases and flame immediately above the coal, the construction being such that the air is gradually heated until it is discharged at the inner and hottest end of the device.

A further object of the invention, more specifically, is to provide an air heater formed in sections and with an air shutter or control device exterior of the furnace, the parts being so arranged that the sections will be interior of the furnace when the furnace door is shut.

In the accompanying drawing—

Fig. 1 is a fragmentary perspective view of a conventional furnace with an embodiment of the invention applied thereto;

Fig. 2 is a longitudinal vertical sectional view through the air heating device shown in Fig. 1, the same being on an enlarged scale;

Fig. 3 is a fragmentary side view showing several of the sections illustrated in Fig. 2;

Fig. 4 is a front view of the device as it is viewed from the outside of the furnace door;

Fig. 5 is a sectional view through Fig. 2 on the line 5—5;

Fig. 6 is a sectional view through Fig. 2 on the line 6—6;

Fig. 7 is a sectional view through Fig. 2 on the line 7—7;

Fig. 8 is a sectional view through Fig. 2 on the line 8—8;

Fig. 9 is a sectional view through Fig. 2 on the line 9—9;

Fig. 10 is a sectional view through Fig. 2 on the line 10—10, looking toward the furnace door.

Referring to the accompanying drawing by numerals, 1 indicates an ordinary conventional furnace with the usual door opening 2, through which coal is adapted to be supplied to the furnace. The door 3 is hinged at 4, and is provided with a catch 5 adapted to be fitted into a notched latch member 6. The construction just described is old and well known.

To the door 3 is connected an air heating device

7 constructed according to the present invention. It will be noted that the device is mounted nearer the hinges 4 than the latch 5. This is to permit the device to readily swing in and out of the furnace whenever desired. The device is made of a length to permit the air passing out the apertures 8 to be discharged substantially centrally over the flame. As the device is continually inside the furnace except when coal is being provided, it will become very hot and, consequently, the air passing out the apertures 8 will be substantially the same temperature as the flame or gases rising from the burning coal. By providing heated air of substantially the same temperature as the gases, there will be a ready mixture of the air and gases which will readily ignite and, consequently, the gases will be consumed and produce heat rather than the usual losses that are now experienced. In addition, by burning the gases the usual gas odors are eliminated. It will be seen, therefore, that by providing the heated air as just set forth, objectionable odors are eliminated and a saving of coal is secured by reason of the extra heat usually pass out the chimney.

The heater 7 is provided with a number of sections, there being six sections shown in the accompanying drawing, namely, sections 9, 10, 11, 12, 13 and 14. A spider or fitting 15 is carried by section 9, as shown in Fig. 2, and a pipe 16 is screwed thereon. The pipe 16 extends through an aperture or hole in the door 3 and has a hollow knob 17 thereon exterior of the door. This knob acts in several capacities, including a nut for drawing the parts tightly together, as shown in Fig. 2. One or more washers may be used to space the heater inwardly from the door a short distance. The spider 15 is also provided with a threaded extension 19 into which is screwed one end of a rod 20. This rod extends through suitable centrally positioned apertures in the various sections 10 to 14 inclusive, and the sections are clamped together by a nut 20. It will be observed that each section, except section 14, is provided with an annular notch 21 so that the end or foot portion 22 of the next section may fit therein. Each section, except 9, is provided with a notch 23 for receiving the lugs or extension 24 of the next adjacent section. By this arrangement, as shown in Fig. 3, the various sections are aligned and by the arrangement of the groove or annular notch 21 and ends or feet 22 the parts are overlapped. The rod 20 functions to hold all the

parts tightly together while permitting the same to be separated for repair or other reasons.

Preferably the various sections are formed from cast iron, though they could be made from other material without departing from the spirit of the invention. The knob 17, as illustrated particularly in Fig. 2, is provided with an inlet aperture 25 which when the device is in use registers entirely or partly with an aperture 26 in a rotating plate 10 27, which plate acts as a shutter or damper for regulating the amount of air allowed to enter the heater.

In operation the heater is mounted on a door, as shown in Fig. 1, and when the fire is first 15 started preferably the damper 27 is moved so that the aperture 26 will be out of registry with the aperture 25. However, after the fire has gained some considerable headway and begins to function to produce heat, the shutter is gradually 20 opened and may be set at any desired opening whereupon air will enter the heater and be discharged out through the aperture 8 at a temperature substantially the same as the hot gases and flame in the furnace.

25 It will be observed that the section 10 is provided with a number of apertures 28, while the section 11 is provided with apertures 29. Sections 12 and 13 are provided with apertures 30 and 31, respectively. These apertures are offset from 30 each other so as to provide a more or less tortuous passageway for the air and thereby delay its passage sufficiently to permit it to be heated to the extent above mentioned.

35 By providing heated air above the fire, the unburned gases which usually pass up the chimney are ignited so that a more efficient heating action is secured and, consequently, an appreciable saving of coal. It will be seen, therefore, that the heater performs two principal functions, 40 namely, the function of causing the gas to be consumed rather than pass up the chimney or into the room and, at the same time, results in the production of extra heat by the combustion of these gases.

It will readily be observed that whenever the apertures 25 and 26 are out of alignment the heater will not function and, consequently, the furnace will function in the usual way of furnaces of the particular type used. However, as soon as 5 the plate or disk 27 is rotated somewhat, so as to cause a registry or partial registry of apertures 25 and 26, the heater will begin to function to supply heated air to mix with the flame and the hot gases in the furnace to secure a better combustion of the coal.

10 I claim:

An air heater for a furnace having a door, comprising a tubular member positioned to extend through said door, an air control valve connected 15 to said tubular member exteriorly of the door, an end heating section positioned interiorly of the door formed with a central bore having an enlarged portion whereby an annular shoulder is presented, a spider partly positioned in the bore 20 in said section, said spider having an interiorly threaded tubular sleeve fitting in said central bore, a flange fitting against said shoulder and a threaded extension, said tubular member being screwed into said interiorly threaded tubular sleeve for clamping said section against the interior of said door, a series of separable partly 25 overlapping cup-shaped heating sections, one of said series of heating sections partly overlapping said end heating section, each of said series of heating sections being fully open at one end and at the other end being provided with apertures, 30 the apertures in all of said series of heating sections being offset from the next adjacent heating section so as to cause air passing through the heating sections to move in a tortuous passageway, and a rod extending substantially centrally through all of said series of heating sections, said 35 rod at the end adjacent said end heating section being screwed into said threaded extension and a clamping nut on the other end for clamping all 40 said heating sections together.

GIUSEPPE ALFISI.
